(57) **CLAIM**

The ornamental design for a shoe, as shown and described.

DESCRIPTION

FIG. 1 is a top view of a shoe showing our new design;

FIG. 2 is a bottom view thereof;

FIG. 3 is a front view thereof;

FIG. 4 is a rear view thereof;

FIG. 5 is a first side view thereof;

FIG. 6 is a second side view thereof; and,

FIG. 7 is a front perspective view thereof.

The long and short broken lines form a boundary of the shoe and form no part of the claimed design. The four unshaded oval portions within the shoe surface form no part of the claimed design.
